Primary Examiner — Susan Bennett Hattan*Assistant Examiner* — Leanne Was(74) *Attorney, Agent, or Firm* — Renner, Otto, Boisselle & Sklar, LLP(57) **CLAIM**

The ornamental design for a microphone, as shown and described.

DESCRIPTION

FIG. 1 is a perspective view of a microphone showing our new design.

FIG. 2 is another perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines shown herein depict portions of the microphone that form no part of the claimed design.

1 Claim, 5 Drawing Sheets(56)
